OIL BURNER

Thure A. Quart, Hartford, Conn.

Application July 5, 1932, Serial No. 620,866

2 Claims. (Cl. 158—88)

My invention relates to that class of oil burners which are designed to burn oil by first vaporizing the same and then burning the vapor thereof between concentric cylindrical perforated shells.

It is customary in this type of burners to provide a base on which are mounted two or more perforated shells, the number depending on the size of the burner. These shells are removable from the base, and due to their comparatively light weight must be closely fitted to said base in order to keep them fixed in their proper position so that air will not pass under said shells in sufficient quantity to cause a faulty flame in the burner.

It is occasionally necessary to remove the shells from the burner base. On the burners now commonly used this is done with considerable difficulty, due to the fact that each shell must be removed separately. Due to the close fit necessary, the shells often adhere to the base, and in removing them the adjustment of the burner base is disturbed.

An object of my invention is to provide means whereby all of the shells including shell-covers and vaporizing cover are contained in one single and complete unit and can be easily mounted on or removed from the burner base as a unit.

A further object of my invention is to provide a burner base which is highly efficient in operation, simple in construction and economical to manufacture.

One form of a burner embodying my invention, and in the construction and use of which these objects may be attained is illustrated in the accompanying drawings, in which:

Fig. 1 is a plan view of my improved burner.

Fig. 2 is an elevation in central vertical section thereof.

Fig. 3 is a plan view of my improved base showing a part of the vaporizing cover mounted thereon.

Fig. 4 is a view in vertical section of the base on line 4—4 of Fig. 3.

Fig. 5 is a bottom view of the complete shell unit.

Fig. 6 is a fragmentary view in section on line 6—6 of Fig. 3.

In the drawings the numeral 5 denotes the burner base which is cast at the end of a supporting bar 6, and mounted on a post 7 which can be supported in any desired manner.

If desired a similar base can be cast at the other end of bar 6, providing a double burner base.

55 The base contains annular concentric vapor

grooves 8 and 9 and a vaporizing groove 10, located adjacent to the inner vapor groove 9. Notches 11 are formed in the inner wall 12 of the inner vapor groove and communicating grooves 13 extend across air spaces 14 between the vapor grooves 9 and 8. These notches 11 and grooves 13 provide for the passage of vapors from the vaporizing groove 10 to each of the vapor grooves.

A boss 15 is provided on the bottom of the burner base 5, which contains a fuel well 16 opening into the vaporizing groove 10. The bottom of this well is closed with a plug 17, and a fuel supply pipe 18 is secured to the side of the boss 15 for supplying fuel to the vaporizing groove 10 through the well 16. This construction of the burner base provides a trap at the bottom of the fuel well 16 which can easily be cleaned out by removing the plug 17.

Locating lips 19 and supporting shoulders 20 are formed at the upper edges of the walls, forming the various grooves, for the purpose of supporting the shell unit and maintaining the same in proper position thereon.

The shoulders 21 surrounding the vaporizing groove 10 on the wall 12 are slightly lower than the shoulders 20, and extend into notches 11 at each side thereof. Shoulders 12 are provided at each side of the connecting grooves 13 on the same plane as the shoulders 21.

Starting wicks of asbestos material are mounted within the vapor grooves 8 and 9. The wick 23 in the outer groove being continuous while the wick in the inner groove is divided into sections, each section being interposed between the vapor passages 13 so as to permit free passage of vapor therethrough.

The various parts comprising the shell unit consist of a plate 25, perforated shells 26, cover plate 27 and handle 28.

The plate 25 comprises an annular vaporizing cover section 29 having a stiffening boss 30 formed therein and radially disposed extensions 31 extending therefrom.

Shell locating lips 32 are upturned from each extension 31 for locating the inner shells on the plate 25 and the outer ends of the extensions are formed to provide walls 33 and lips 34 for locating the two outer shells thereon. The ends of extensions 31 are also formed to provide wick retaining notches 35.

The cover plate 27 is formed to provide a central cover disc section 36 and ring cover section 37.

The disc and ring section of the cover are 55

joined by connecting bars 38 which extend between air openings 39 in the cover plate.

5 Radial extensions 40 are provided at the outer edges of the ring section and the ends thereof are upturned as at 41 to fit within the outside shell 26.

The handle 28 is secured to the cover 36 as by spot welding or similar means at the lips 34.

10 Shell retaining walls 43 are formed on the cover plate section 36-37 for the purpose of retaining the shells in concentric position.

15 All of the parts composing the shell unit are secured together in the following manner: first the plate 25 is secured to the outside shell 26 by means of spot welding the shell to the upturned lips 34.

The inner shells are then placed in position on the said plate against the lips 32 and walls 33.

20 The cover plate 27 is then fitted in position as shown in the drawings and spot welded to the outside shell by the upturned lips 41.

25 When thus secured together all of the parts fitting on top of the burner base are contained in a single unit.

30 The shoulders 20 on the burner base are made sufficiently wide to provide proper support for the shells that are made to fit freely against the lips 19. Thus the complete shell unit can be readily placed in position on the burner base or removed therefrom when it is desired to uncover the burner base.

35 It can be seen that this offers a considerable advantage as all of the parts over the burner base with the exception of the wicks can be lifted as a single unit by the handle 28.

Other advantages are obtained by means of the novel design of my device.

40 When lighting the burner wicks with a taper as is customarily done, the wicks are moved from their proper position so that often the passage of vapor through the vapor passages is obstructed. I have overcome this objection by means of the extensions 31 on the plate 25 and the wick retaining notches 35 at the outer ends thereof. In 45 order to provide free passage of vapor around the outer vapor groove it is essential that the wick 23 be held in position against the outside of vapor groove 8 so that the said wick will not obstruct the passage of vapor through the 50 grooves 13 into the said vapor groove. When the shell assembly is placed on the burner base the outer wick is forced in position by the inclined sides 44 until the said wick rests within the retaining notches 35, thus preventing the 55 said wick from closing the grooves 13.

It is also essential that the sections of the inner wick 24 be retained in proper position so that they cannot obstruct the vapor passages 13. This I have accomplished by means of the 60 plate extensions 31 which lie over the vapor passage grooves 13 at a level below the top of the wick sections and thus prevent said sections from moving into the path of the vapors passing through said grooves.

65 When the shell unit is placed in position on

the burner base, the plate 25 will rest on the shoulders 21 around the vaporizing groove 10 and the extensions 31 of said plate will rest on the shoulders 22 at the sides of passage grooves 13, thus forming a complete cover for said vaporizing groove and passage grooves. 5

The operation of my improved burner is as follows: Oil is first admitted into the bottom of the vaporizing groove, vapor passage grooves, and vapor grooves to flood the bottom of said grooves and to saturate the starting wicks. The wicks are then ignited through the slots in the shell-cover 27 by means of a taper or similar device. The oil at the bottom of the grooves is thus burned at the said wicks until the burner 15 base has become heated to a degree sufficient to vaporize the oil as it enters into the vaporizing groove 10.

20 The vapors now formed in the vaporizing groove 10 will pass from said vaporizing groove through notches 11 and vapor passages 13 into vapor grooves 8 and 9, from where they will rise into the combustion chambers 47-48.

25 The heat within the burner will cause an upward passage of air through the central opening 45 and air spaces 14. This air is prevented from passing through the top of the burner by the shell cover plate section 36-37. It will thus be forced to pass through the perforations in the shells into the combustion chambers, where 30 said air will mix with the oil vapors therein and provide proper combustion.

35 In Fig. 1 of the drawings I have illustrated a novel construction which is both economical and efficient in adjustably securing the burner to the supporting post 7. I provide a hole in the bar 16 which is shaped so that the bar 7 will contact at only two points within said hole. The clamping screw 50 is threaded through the wall into said hole to clamp the post 7 from one side there- 40 of against the two contacting surfaces, thus providing a three point contact as a means for rigidly securing my burner to said post. This form of a hole can be easily cast into the bar 16 as no accuracy is required for a proper fit on 45 account of its shape.

I claim:

1. A burner of the character described comprising a base having vapor grooves therein, vapor passages communicating with said grooves, 50 means for supplying fuel to said grooves, wicks mounted in said grooves, a cover plate on said base, and means on said cover plate for retaining said wicks in position and spaced from said vapor passages. 55

2. A burner comprising a base having inner and outer fuel grooves therein and means for supplying fuel to said grooves, a wick positioned within the outer groove, a plurality of wicks positioned within the inner groove, a removable 60 cover on said base, and means on said cover for retaining the wicks in the inner groove against rotational movement and the wick in the outer groove against radial movement therein. 65

THURE A. QUART. 65
